(57) **CLAIM**

The ornamental design for a conduit coupling, as shown and described.

DESCRIPTION

FIG. 1 is a left perspective view of a conduit coupling of the present invention;

FIG. 2 is a top plan view of the conduit coupling of FIG. 1; FIG. 3 is a right side view of the conduit coupling of FIG. 1;

FIG. 4 is a left side view of the conduit coupling of FIG. 1; FIG. 5 is a bottom plan view of the conduit coupling of FIG. 1;

FIG. 6 is a rear elevational view of the conduit coupling of FIG. 1;

FIG. 7 is a front elevational view of the conduit coupling of FIG. 1; and,

FIG. 8 is a left perspective view of a second embodiment of the conduit coupling of FIG. 1.

The top, right, left, bottom, rear and front views of the second embodiment being similar to FIGS. 2–7, respectively.

The matter shown in phantom lines in FIGS. 1–2 and 5 is for illustrative purposes only and forms no part of the claimed design.
